*Fig. 3**Fig. 4**Fig. 5*

FIGURE 1 is a perspective view of a light accessory for a bicycle showing my new design;

FIGURE 2 is a side elevational view thereof, a portion of the bracket being omitted for convenience of illustration;

FIGURE 3 is a top plan view thereof, a portion of the bracket being omitted for convenience of illustration;

FIGURE 4 is a rear elevational view thereof, a portion of the bracket being omitted for convenience of illustration; and

FIGURE 5 is a front elevational view thereof, a portion of the bracket being omitted for convenience of illustration.

The fragmentary portion of the bicycle shown in broken lines in FIGURE 1 is included for illustrative purposes only.

This application is a division of my copending application, Serial No. D-80,397, filed June 15, 1964, now Patent Des. 203,064.

I claim:

The ornamental design for a bicycle light, substantially as shown and described.
